CLAIM

The ornamental design for a surgical flap dissector instrument, as shown and described.

DESCRIPTION

FIG. 1 is a front perspective view from above of a surgical flap dissector instrument, open;

FIG. 2 is a rear perspective view from below of the surgical flap dissector instrument, open;

FIG. 3 is a front perspective view from above of the surgical flap dissector instrument, closed;

FIG. 4 is a front view of the surgical flap dissector instrument, open;

FIG. 5 is a front view of the surgical flap dissector instrument, closed;

FIG. 6 is a rear view of the surgical flap dissector instrument, open;

FIG. 7 is a left-side view of the surgical flap dissector instrument, closed;

FIG. 8 is a right-side view of the surgical flap dissector instrument, closed;

FIG. 9 is a top view of the surgical flap dissector instrument, open;

FIG. 10 is a top view of the surgical flap dissector instrument, closed;

FIG. 11 is an underneath view of the surgical flap dissector instrument, open; and,

FIG. 12 is an underneath view of the surgical flap dissector instrument, closed.

The broken lines shown illustrate portions of the surgical flap dissector instrument that form no part of the claimed design.

1 Claim, 8 Drawing Sheets
